UNITED STATES PATENT OFFICE.

JOHN T. HAWKINS, OF TAUNTON, MASSACHUSETTS.

MEANS FOR SECURING CURVED FORM-PLATES IN ROTARY PRINTING-MACHINES.

SPECIFICATION forming part of Letters Patent No. 361,821, dated April 26, 1887.

Application filed July 8, 1886. Serial No. 207,417. (No model.)

To all whom it may concern:

Be it known that I, JOHN T. HAWKINS, of Taunton, in the county of Bristol and State of Massachusetts, have invented a new and useful Means for Securing Curved Form-Plates to the Cylinders of Rotary Printing-Machines, which invention or improvement is fully set forth and illustrated in the following specification and accompanying drawings.

10 The object of this invention is to provide a simple and reliable means for securing curved plates for book or pamphlet forms on the cylindrical surface of the printing-cylinder of a rotary printing-machine in such a way that 15 the dimensions and positions of the page-plates may be changed at will.

In the printing from book or pamphlet forms made up of pages of matter and intervening blank margins, it is desirable to have 20 for each page a separate plate, and in order to print forms of that character containing pages and blank margins of different dimensions it becomes necessary to secure a plate of any size upon any chosen spot of the printing or form cylinder. This has heretofore 25 been done by making dovetailed or rabbeted grooves either in the surface of the cylinder or in the turtles parallel with the cylinder's axis, and sliding therein correspondingly. 30 shaped blocks, portions of which project above the cylinder's surface, and by means of end screws and said blocks clamping the plates by end pressure in the direction of the cylinder's axis; and in some cases circumferential 35 grooves of similar character with sliding blocks have been used for holding the plates in the other direction. These grooves, however, being fixed in position, permit only of a limited variation in the sizes of the plates.

40 Another method has been to screw the plates fast to the surface of the turtle or cylinder by drilling through blank places in the plates, the surface of the turtle or cylinder being drilled or tapped in the corresponding 45 positions for the reception of screws. Many plates, however, cannot be so drilled, and the drilling and tapping of holes indiscriminately in the turtle or cylinder soon becomes objectionable, a hole thus drilled rarely being required a second time in the same place.

This invention consists in the combination of adjustable clamps with a cylinder or turtle constructed with screw-holes in the surface thereof regularly, and so closely spaced and staggered that, for any size of plate, a row of 55 said holes shall always present themselves in the margin-spaces between such plates, and whose diameters shall bear such proportion to the thickness of the plate used that the plate will be perfectly supported against distortion under the pressure of printing by all 60 that portion of the surface not drilled and tapped, so that said plates, rabbeted on edge and held by said clamps formed to lie upon these rabbeted edges, may be secured by screws 65 in the regularly-spaced screw-holes above mentioned, thus holding the plates by direct pressure upon the cylinder's surface.

In the accompanying drawings, Figure 1 is a view, in plan, of a turtle or form-bed constructed according to my invention, the upper left-hand quarter of which is shown without plates upon it, the other three-quarters having portions of a sixteen-page form secured thereto. Fig. 2 is a side elevation, 70 Fig. 3 a sectional end elevation, of Fig. 1. Fig. 4 is an enlarged sectional view showing more clearly the form of clamp and plate; and Fig. 5 shows a clamp, on an enlarged scale, slotted for the reception of the screw-head.

In said figures the several parts are indicated by numbers, as follows: 1 indicates the turtle; 2, the plates; 3, the clamps; 4, the screw-holes, and 5 the screws. The slotted 85 clamps, as shown in Fig. 5, it will be seen, will permit of their use even when the screw-holes do not present themselves in the center of the margin-spaces, as may sometimes be the case.

I do not claim, broadly, the securing of plates to a turtle by means of clamps and screws; but,

As of my invention, I claim—

In a rotary printing-machine, in combination with a cylinder or turtle provided with a fixed series of screw-threaded holes, as 4, closely spaced and staggered in the surface thereof, a series of adjustable clamps, as 3, secured to said cylinder by screws, as 5, whose 95 100

limit of adjustment corresponds with the distance between said screw-holes, whereby any number of rabbeted plates of any desired dimensions within the area limit of the cylinder or turtle may be secured upon said cylinder or turtle without end-thrust upon said plates, and each plate also made separately adjust-

able upon the said cylinder or turtle without disturbing the others, substantially as and for the purposes set forth.

JOHN T. HAWKINS.
